UNITED STATES PATENT OFFICE.

WILLIAM S. WELLS, OF BETHLEHEM, PENNSYLVANIA, ASSIGNOR TO BENJAMIN EASTWOOD COMPANY, OF PATERSON, NEW JERSEY, A CORPORATION OF NEW JERSEY.

TAKE-UP MECHANISM FOR LOOMS.

Application filed April 2, 1923. Serial No. 629,273.

To all whom it may concern:

Be it known that I, WILLIAM S. WELLS, a citizen of the United States, residing at Bethlehem, in the county of Lehigh and 5 State of Pennsylvania, have invented certain new and useful Improvements in Take-Up Mechanisms for Looms, of which the following is a specification.

This invention relates to take-up mechanisms for looms, and it consists in an improved take-up mechanism by which the sheet of woven cloth and warp can be maintained at any desired tension, the cloth-beam being allowed to slip relatively to its 10 driver so as to compensate for the continuing increase in diameter of the cloth wound thereon and having a coupling means through which it is disconnectively connected with the driver and which may be 15 operated by the weaver so as to release the beam for rotating it backward, freely, whenever occasion demands.

In the drawings,

Fig. 1 is a rear elevation of the improved 20 mechanism;

Fig. 2 a side elevation thereof, a part of the loom frame appearing in section;

Fig. 3 is a view showing the shaft of the 25 cloth beam in elevation and the coupling and driver in section;

Fig. 4 is an inside face view of the parts shown in Fig. 3, partly in section and partly broken away;

Fig. 5 is an outside face view, partly 30 broken away;

Fig. 6 is a view similar to Fig. 5, with the clamping wheel and nut removed;

Fig. 7 shows one of the friction-disks; and

Fig. 8 shows a certain key or spline.

40 In a bracket *a* forming part of the supporting structure of a loom is journaled the shaft or shaft portion *b* of a beam *c*, it being understood that the beam is fixed on its shaft. The shaft has a pin *d* driven through 45 a hole therein so that both ends project, the pin forming a detent. The end of the shaft is reduced and threaded as at *e*.

A coupling member is formed by a bushing *f* which is penetrated by the shaft. It 50 has at its inner end an enlarged head *f'* which is formed with diametric grooves *f''* equally spaced. The other end of the bushing is exteriorly threaded, as at *f''*. The bushing further has a longitudinal exterior groove *f'''* which may extend from end to end

thereof. The coupling *f* may be interlocked with the beam to rotate therewith by turning a hand-clamping wheel *g*, which is screwed onto the threaded portion *e* of the shaft, so that the pin *d* is engaged in one 60 of the grooves *f''*.

h is the driver, being a gear freely revolvable on the bushing; it may form a part of a gear train one of which, *i*, is shown in Fig. 1. In the preferred form it has in its web, 65 penetrating the same and projecting from both sides thereof, inserts *h'* of cork or other suitable material that will afford a good friction grip.

On each side of the driver and penetrated by the bushing is a friction disk *j*, one of which is adapted to abut the enlarged head *f'* of the bushing. Against the other disk bears a triangular plate spring *k* which is penetrated by the bushing, its 70 three extremities being bent inward and its central portion being subject to the pressure of a nut *l* screwed on the threaded portion *f''* of the bushing. Whereas the driver *h* is adapted to revolve on the bushing the two 75 disks are held against revolving with respect to the bushing by a spline *m* which is set in the groove *f'''* of the bushing and has two outward projections *m'* spaced sufficiently to admit the driver between them 80 and engaged in notches *j'* formed in the disks. Thus the driver is capable of slippage rotatively relatively to the beam, such resistance as is opposed thereto being determined by the degree of clamping pressure 85 effected as between *f'* and *l* when the latter is screwed up against the spring *k*.

When the device is in use the weaver screws up the nut *l* to produce that degree 90 of clamping pressure which will maintain the desired degree of tension on the sheet of cloth and warp designated A in Figs. 1 and 2. As the diameter of the windings of cloth increases on the beam there will be a compensating slippage of the driver relatively to the beam, and if necessary the weaver may from time to time further screw up the nut 95 *l* to maintain the predetermined tension. Whenever it is necessary for the weaver to release the beam from the driver so that he 100 may rotate it backward, he turns back the wheel *g*, which releases the interlock at *d* *f''*.

It will be seen that the construction is quite simple and inexpensive and that the device may be readily applied to any exist- 110

ing loom without material change therein. The two disks, which afford broad friction surfaces on both sides of the driver, are locked to the rotating structure $b-f$ by a simple expedient consisting of the peculiar spline m , which nevertheless allows the driver to slip rotatively relatively to the disks, the necessary frictional resistance being obtained by nut l and the shoulder 10 formed on said structure at the inner side of head f' coacting to clamp the disks and driver between them.

Having thus fully described my invention, what I claim as new and desire to secure 15 by Letters Patent is:—

1. In a loom, the combination of a supporting structure, a beam journaled therein, a coupling member for the beam adapted to revolve concentrically thereon, said beam 20 and member having releasable means to interlock them for rotation together, means to drive the beam including a driver concentric with the beam, and means to maintain a slip-friction-grip between the driver and 25 coupling member.

2. In a loom, the combination of a supporting structure, a beam journaled therein, a coupling member for the beam adapted to revolve concentrically thereon and shiftable 30 axially thereof and said beam and member having portions adapted to interlock them on shifting said member in one direction, means to shift said member into and hold it in 35 interlocked engagement with the beam, means to drive the beam including a driver

concentric with the beam, and means to maintain a slip-friction-grip between the driver and coupling member.

3. In a loom, the combination of a supporting structure, a beam journaled therein, 40 a coupling bushing for the beam adapted to revolve concentrically thereon and shiftable axially thereof, said bushing having at one end an enlarged head and the beam and head having interlockable portions, means 45 at the other end of the bushing to shift the latter in the direction to interlock said portions, means to drive the beam including a driver concentric with and revoluble on said bushing, and means on the bushing coacting 50 with said head to exert slip-friction-clamping pressure on the driver.

4. In a loom, the combination of a supporting structure, a rotary structure journaled therein and having a shoulder and also 55 a longitudinal groove lateral of the shoulder, a driver for the rotary structure concentric with the grooved portion thereof, a pair of clamping members penetrated by the grooved portion of said rotary structure and arranged 60 one on each side of the driver, means coactive with said shoulder to cause said members to clamp the driver, and a spline engaged in the groove and contained in said members and driver, the driver being revoluble independently of said spline but the spline having on each side of the driver projections interlocked with said members.

In testimony whereof I affix my signature.

WILLIAM S. WELLS.
